DIVING TOY SUBMARINE

Filed June 27, 1927

UNITED STATES PATENT OFFICE

JOHN J. MACKINTOSH, OF PORT RICHMOND, NEW YORK

DIVING TOY SUBMARINE

Application filed June 27, 1927. Serial No. 201,711.

This invention relates to toys in general and to a diving toy submarine in particular.

The primary object of the invention resides in a toy submarine of a buoyant nature 5 to normally float upon the surface of a body of water but which may be made to dive or submerge below the surface until the same strikes bottom at which time it will automatically rise to the surface and which simulates 10 the actions of a submarine war craft.

Another object of the invention is to provide a toy submarine which has an inclined passage or chute at the forward end or bow thereof which is closed at its lower end by 15 a door to block the passage of a weighted ball therethrough to cause the toy to dive bow first and entirely submerge, and a means automatically operable when the toy reaches bottom to open the door to release the 20 weighted ball whereupon the toy submarine is free to return to the surface of the water under its own buoyancy.

A further object of the invention is the 25 provision of a toy boat having an open ballast compartment in its underside which automatically fills with water when the body is placed therein to maintain the same on an even keel and prevent accidental capsizing of the toy.

A still further object is to provide a toy 30 submarine which is simple in operation so that a child can operate the same, and from which much pleasure may be derived in watching the actions of the same.

With these and other objects in view, the 35 invention resides in certain novel construction and combination and arrangement of parts, the essential features of which are 40 hereinafter fully described, are particularly pointed out in the appended claims, and are illustrated in the accompanying drawing in which:—

Figure 1 is a side elevation of improved 45 toy submarine on the surface of a body of water.

Figure 2 is a similar view showing the 50 same in a partially submerged condition and with a portion broken away in section.

Figure 3 is a view similar to Figure 2 but

showing the toy submarine in engagement with the bottom of a body of water.

Figure 4 is an enlarged vertical sectional view through the toy submarine.

Figure 5 is a vertical transverse sectional 55 view on the line 5—5 of Figure 4.

Figure 6 is a detail perspective view of the weight member.

Referring more particularly to the drawing, the reference numeral 10 designates my 60 submarine toy in its entirety which includes a buoyant body 11 of a shape simulating the general outline of a real submarine by having a conning tower 12 rising therefrom together with certain other like parts. The 65 body or hull 11 may be constructed of wood, metal or other buoyant material and has its underside cut-away at the stern as at 13 to accommodate a propeller shaft 14 having a propeller 15 thereon and which may be driven 70 by any suitable mechanism. The body is provided with a chamber 16 which opens into the cut-away portion 13 through a recess 17 and which chamber and recess are disposed below the water line of the body so 75 as to automatically fill up with water when placed therein. The water fills the chamber 16 and serves as a ballast for the toy for preventing the same from accidentally tipping over.

The body 11 is provided at its forward end with an inclined passage or chute 18, one end of which opens through a conning tower 12 while the opposite end terminates at the bow adjacent the keel and which is 80 normally closed by a hinged door 19, held in a closed position by a keeper 20 fixed to a flat bow spring 21, which has one end fastened to the underside of the body and its free end extending downwardly below the underside 85 of the body and rolled as at 22. The normal tendency of the spring is to hold the keeper 20 in engagement with the door 19 to prevent accidental opening thereof.

A door 23 is hinged to the conning tower 90 for normally closing the top of the inclined passage 18.

For use in causing the diving of the submarine, I provide a spherical weight 24 fixed to one end of a length of cord 25, while the 100

other end of the cord carries a float 26. The length of the cord is dependent upon the depth of the body of water in which the toy is adapted to be submerged, for the greater 5 the depth of the body of water, the longer will be the cord.

In operation, the toy submarine may be made to float upon the surface of the body of water W as shown in Figures 1 and 4 of 10 the drawing, but when it is desired to cause the same to dive, the door 23 is lifted and the weight 24 dropped into the inclined passage 18. As the weight rolls toward the door 19, the front end of the toy will gradually sink 15 beneath the surface of the water and will carry the entire body downward bow first until the free end 22 of the spring 21 hits the bottom B which causes the flexing of the spring and in turn releases the keeper 20 from engagement with the door 19, whereupon the weight drops from the body to the 20 bottom B. By releasing the weight 24, the buoyant nature of the toy will gradually cause the same to return to the surface of 25 the water.

The weight 24 may be retrieved as the float 26 remains upon the surface. The boat may now be removed from the water and the door 19 closed behind the keeper 20 whereupon the submarine is again ready for diving.

This submarine toy will be found most interesting for children as a great deal of amusement may be derived from watching the diving and the return of the boat to the surface 35 of the water.

While I have described what I deem to be the most desirable embodiment of my invention, it is obvious that many of the details may be varied without in any way departing 40 from the spirit of my invention, and I therefore do not limit myself to the exact details of construction herein set forth nor to anything less than the whole of my invention limited only by the appended claims.

45 What is claimed as new is:—

1. A toy diving boat simulating a submarine comprising a buoyant body having an inclined passage therein extending lengthwise of said body, one end which opens above the water-line and the other end below the water-line, a hinged door closing the lower end of said passage, a bowed spring fixed to said body and the free end thereof extending downward, a keeper carried by said bowed spring and normally in engagement with said door to hold the same closed, and a weighted member adapted to be placed into said passage for overcoming the buoyancy of said body when placed within a body of water, the free end of said spring adapted to engage the solid substance at the bottom of the body of water whereby to be flexed to release said keeper from engagement with said door to permit said weight member to drop from said body.

- 63 2. A toy diving boat simulating a subma-

rine comprising a buoyant body having an inclined passage therein, one end of which opens amidships above the water-line and the other end forward below the water-line at one end of the body, a hinged door closing the lower end of said passage, a bowed spring fixed to said body and the free end thereof extending downward, a keeper carried by said bowed spring and normally in engagement with said door to hold the same closed, and a weighted member adapted to be placed into said passage for overcoming the buoyancy of said body when placed within a body of water, the free end of said spring adapted to engage the solid substance at the bottom of the body of water whereby to be flexed to release said keeper from engagement with said door to permit said weight member to drop from said body, and means attached to said weight member by which the same may be retrieved from the surface of the body of water.

3. A toy diving boat simulating a submarine comprising a buoyant body having an inclined passage therein, one end of which opens amidships above the water-line and the other end forward below the water-line at one end of the body, a hinged door closing the lower end of said passage, a bowed spring fixed to said body and the free end thereof extending downward, a keeper carried by said bowed spring and normally in engagement with said door to hold the same closed, and a weighted member adapted to be placed into said passage for overcoming the buoyancy of said body when placed within a body of water, the free end of said spring adapted to engage the solid substance at the bottom of the body of water whereby to be flexed to release said keeper from engagement with said door to permit said weight member to drop from said body, a flexible element having one end attached to said weight member, and a float attached to the other end of said flexible element.

4. A toy diving boat simulating a submarine comprising a buoyant body having an inclined passage therein, one end of which opens onto the top of said buoyant body while the opposite end opens at one end thereof, a door at the lower end of said passage, keeper means for normally holding said door in a closed position, a weight member insertible into said passage through the top open end and adapted to move toward the closed end thereof to cause the sinking of said buoyant body end first when placed in a body of water, and automatic means for releasing said keeper means from engagement with said door, thereby dropping said weight when the buoyant body sinks to the solid substance at the bottom of the body of water.

In testimony whereof I have affixed my signature.

JOHN J. MACKINTOSH.
